DESIGN FOR AN X-RAY CASSETTE TUNNEL

Donald A. Eddy, Park Hills, Ky., assignor to The Kelley-Koett Manufacturing Company, Incorporated, Covington, Ky., a corporation of Ohio

Application March 13, 1939, Serial No. 83,530

Term of patent 14 years

To all whom it may concern:

Be it known that I, Donald A. Eddy, a citizen of the United States, residing at Park Hills, in the county of Kenton and State of Kentucky, have invented a new, original, and ornamental Design for an X-Ray Cassette Tunnel, of which the following is a specification, reference being had to the accompanying drawing, forming part thereof.

Figure 1 is a front view of an X-ray cassette tunnel, according to my design.

Figure 2 is a side elevation of said cassette tunnel.

Figure 3 is an end view.

I claim:

The ornamental design for an X-ray cassette tunnel, substantially as shown.

DONALD A. EDDY.
